RADIO BEACON SYSTEM

Emile Labin, New York, and Donald D. Grieg,
Forest Hills, N. Y., assignors to Federal Tele-
phone and Radio Corporation, New York, N. Y.,
a corporation of Delaware

Application March 10, 1945, Serial No. 581,974

14 Claims. (Cl. 343—106)

1

This invention relates to radio beacons and more particularly to radio beacon systems of the omnidirectional type.

Various forms of omnidirectional radio beacons have been proposed in the past. One such form contemplates the directive transmission of a radio beam rotated about an axis. To the beam are applied modulating signals producing different characteristic signals for the different directions of transmission of the beam. This energy is received at one or more receiving points about the beacon. In response to the received characteristic signal energy, the direction of the receiver with respect to the beacon can then be ascertained. If the receiver is mounted on a craft, the craft can then follow a substantially straight line to the beacon by maintaining in the receiver output the same characteristic signal.

It is an object of our invention to provide a radio beacon system in which the beacon signal is characterized by two different signals varying in amplitude relative to one another in accordance with rotation of a beacon beam according to sine and cosine functions respectively.

It is a further object of our invention to provide a receiver responsive to the transmitted beacon signals for separating the separate sine and cosine signals and producing a directional indication in accordance therewith.

It is a further object of our invention to provide a radio beacon system in which the radio beacon transmitter transmits energy producing sine and cosine envelopes at a receiver point and in which a further signal is provided to render these envelopes at the receiver point usable to produce indications in 360° angles.

It is a still further object of our invention to provide a radio beacon system of the general type outlined above in which the transmitter and receiver apparatus can be converted for operation on signals in the general form of sine and cosine functions.

It is a still further object of our invention to provide a ratiometer transmitter adapter unit for a rotatable radio beacon and/or a receiver indicator supply unit for a radio receiver adapted to cooperate with a known type of radio beacon such as outlined above.

According to a feature of our invention, a ratiometer transmitter adapter unit is provided for modulating the radio frequency energy supplied to a rotatable beam transmitter. This ratiometer adapter unit may comprise three sources of signal energy of different frequencies. Energy from two of the sources is modulated in amplitude in accordance with sine and cosine functions respectively. Preferably these sine and cosine functions are of the form $(1+\sin)$ and $(1+\cos)$ respectively, so that when they are used to modulate a radio frequency signal the true

2

sine and cosine envelopes will be transmitted. The third signal supplied is of a constant amplitude and preferably of a value substantially equal to $\frac{1}{2}$ the sine and cosine function energy. These three signals are then used to modulate the energy in the radio transmitter, which may take the form of PTM (pulse time modulation), FM (frequency modulation), or AM (amplitude modulation), so that the radiated beam carries along these three modulation functions. The sine and cosine functions are caused to vary in accordance with the rotatable position of the radio frequency beam. As a consequence, the radiation pattern will contain the first and second frequency signals at different ratios for different directions of the transmitting beam.

For cooperation with this beacon is provided a radio receiver unit which will receive and detect the radio frequency beam energy. In the output of the receiver-detector unit, the three signals are then separated, for example, by filters tuned to the respective frequencies. These separated signals may then be applied to two combining circuits for subtracting the envelope of the third frequency from the envelopes of the other two. As a result there will be two output energies one proportional to the sine function and the other proportional to the cosine function. These two energies may then be applied to a ratiometer to measure the ratio of the energies received producing thereby an indication of direction. Preferably there is provided a means for finding the effective center of the radio beam so that the indicator will show the true ratio between the signal energies at the beam center rather than on the leading or trailing edges of the beam.

A better understanding of our invention and the objects and features thereof may be had from the particular description thereof made with reference to the accompanying drawings, in which:

Fig. 1 is a block circuit diagram of a beacon transmitter and receiver in accordance with our invention; and

Fig. 2 is a set of curves used in explaining the operation of the system in accordance with our invention.

Turning first to Fig. 1, there is illustrated at 1 a radio frequency transmitter coupled to a directive antenna 2. Antenna 2 may be of any desired type and preferably produces a unidirectional radio beam. Motor 3 serves through the medium of a shaft 4 to rotate antenna 2 at a predetermined rate thus producing a rotation of the beam. The adapter unit coupled to the transmitter and antenna arrangement for producing signals varying in ratio about the transmitter as the beam is rotated comprises three oscillators 5, 6 and 7 serving to produce different

3 frequencies F_1 , F_2 and F_3 preferably within the audio frequency band. Oscillators 5 and 6 are coupled to stator coils 8 and 9 of a vario coupler device 10. A rotor 11 is provided in vario coupler device 10 cooperating with stator coils 8 and 9. Rotor 11 is driven in synchronism with rotatable antenna 2 as indicated by the shaft 12. It will therefore be seen that the energy at frequency F_1 and frequency F_2 will vary in amplitude in rotor 11 in accordance with the expression $\sin \theta t$ where θ represents the angular speed of rotation of the rotor coil 11 and antenna 2 and t represents the time. If these two energies present in coil 11 are used without change to modulate the radio frequency of transmitter 1 then the envelopes would not represent true sine wave rotation since each half cycle of each of the waves would provide double side bands having components of twice the fundamental frequency. Accordingly, at transmitter 1 the energy from coil 11 is applied over line 13 and other energy of frequencies F_1 and F_2 is simultaneously applied over lines 14 and 15 respectively. The energy supplied in lines 14 and 15 is such as to add properly to that supplied from coil 11 producing envelopes corresponding with those shown in Fig. 2, curve A, at 16 and 17 respectively, the oscillation waveform between the envelopes being omitted for purposes of clarity. It will be observed that each of these curves varies between zero and a fixed maximum value. Preferably, oscillators 5 and 6 are controlled so that these two waves are of equal amplitudes.

35 The third wave F_3 from oscillator 6 is maintained at a constant amplitude E as shown at curve 18 of Fig. 2 and is applied over a line 19, Fig. 1, to the radio frequency transmitter. Thus in the transmitted radio beam is provided a complex modulation envelope such as indicated by the double curves 16, 17 and 18 of Fig. 2, curve A. Each of these envelopes is of a different frequency. The waveform 16 may be represented by the expression $E(1+\sin \theta t)$ ($\sin 2\pi F_1 t$) or the envelope by the expression $E(1+\sin \theta t)$ curve 17 by $E(1+\cos \theta t)$ ($\sin 2\pi F_2 t$) or the envelope by 45 the expression $E(1+\cos \theta t)$ and curve 18 by the expression $E \sin 2\pi F_3 t$ or the envelope by E .

It will be seen then that in one rotation of the beam from antenna 2, the ratios of energies represented by envelopes 16 and 17 will vary continuously.

55 At a receiver in the field of the beacon there is provided an antenna 20a coupled to a receiver-detector unit 20. This receiver-detector unit serves to produce the envelope frequencies as shown at curve A of Fig. 2. It will be clear, however, that since the entire envelope does not appear at any one point, the receiver will intercept only a small angular portion of the entire sine and cosine wave signals. If it is assumed that the beam is approximately 25° wide then the portion of the envelope effective in the output of receiver-detector 20 will be, for example, that portion contained between lines 21 and 22 of curve A, Fig. 2. For two different positions of the receiver with respect to the beacon, other portions contained between lines 23, 24 and 25, 26, for example, will be received. The energy in the output of receiver-detector 20 is separated into its three signal components F_1 , F_2 and F_3 in separate filters 27, 28 and 29. These filters are preferably very sharp so as to pass substantially only the frequency corresponding to the actual signal components.

The envelope frequencies in the portion pass-

5 ing filters 27, 28 and 29 during the period of reception may be more clearly seen by reference to curve B of Fig. 2. In this figure, taking the component corresponding to the portion between lines 21 and 22, it will be seen that a small portion 30 of envelope 16, a small portion 31 of envelope 17 and a small portion 32 of envelope 18 is present. The energies represented by 10 30 and 31 are not proportional to the sine and cosine because there is added to them the additional energy necessary to transmit the sine and cosine functions. However if the energy represented by level 32 is subtracted from both of these components, as shown in curve C of Fig. 2, these portions of the energy become directly proportional to the pure sine and cosine functions. Accordingly, the output energy from filters 27, 28 and 29 are combined in combining circuits 33, 34 to produce the envelope waves proportional to the pure sine and cosine functions as shown in curve 15 20 C. These combined energies may then be applied to the coils 35 and 36 of a ratiometer 37 and will serve to move the rotor 38 into a position proportional to this received energy.

25 It is clear that if the envelope energies are applied directly to the ratiometer, the rotor 38 will vary in position over the width of the beam starting with the leading edge of the beam when the receiver first becomes sensitive and stopping 30 when the beam passes the receiving antenna. Such an indication then, instead of giving a direct line to the beacon, indicates the edge of the beam. It is difficult for the pilot or operator at the receiver to read the midpoint of the pointer swing. It is therefore desirable to provide some means which will indicate substantially the mid-position of the beam. In the system as illustrated, this beam center finder system comprises integrating circuits 39, 40 and 41 associated respectively, with the outputs of filters 27, 28 and 29. It has been found that when a substantially symmetrical beam produces received energy in the system, the ratio of the total received energies is exactly equal to the ratio of the amplitude of the energies at the mid-position of the beam. Thus, turning back to Fig. 2, the areas under segments 31, 32 and 30 represent the integrated values of the received signals of frequencies F_1 , F_2 and F_3 . The energy under these curves represent then the output voltage of integrators 39, 40 and 41 respectively. The output from integrator 41 is subtracted in combining circuits 33 and 34 respectively, from the output energy of integrators 39 and 40 so that the resultant current in coils 35 and 36 is proportional to the ratio of these integrated values and consequently to the energy at the center of the beam. It will therefore be seen that with the transmitter as described above and the particular receiver circuit, the position of any craft with respect to the beacon may readily be ascertained.

60 While in the system as shown we have indicated that the receiver is such as to respond sharply, producing a segment 21, 22, this action is not necessary to the operation of the system. Regardless of the specific shape or width of the segment of signals received, the ratio of the sine and cosine function energies as received will provide a proper indication of the centering of the beam so long as the build-up and cut-off times of the receiver are substantially symmetrically related.

65 Furthermore, while we have shown the signals as being distinguished by different sub-frequencies, it is clear that any other type of

system for suitably distinguishing the signals may be provided. For example, the signals supplied from the oscillators 5, 6 and 7 may be of pulses of different widths or may be distinguished by some other characteristic. The essential feature is that two of these signals vary in accordance with a sine and cosine function so that in the receiver they may be compared for operating the ratiometer. Furthermore, when other types signals are used, selector circuits for separating these signals other than filters as illustrated may likewise be used.

It further should be understood that while we have shown a vario coupler type of arrangement for providing a sine and cosine variation of the transmitted signal, any other type of transmitter system which would provide the desired variation in synchronism with the antenna rotation may be substituted in its stead. Many other variations in the system in accordance with our invention will occur to those skilled in the art. The specific description of the particular embodiment is given above merely by way of illustration and is not to be considered as a limitation of our invention as set forth in the objects thereof and in the appended claims.

We claim:

1. A receiver for indicating direction with respect to a received signal in the form of a beam rotatable about a given axis, and having two signals varying as sine and cosine functions respectively, in accordance with the rotary position of the beam, and a third signal having a constant value, comprising means for receiving energy from said beam, means for detecting said received energy, means for separating the three signals in said detected energy, means for subtracting said third signal from the first and second signals, and means for comparing the ratios of said subtracted signals to indicate the direction line.

2. A receiver for indicating direction with respect to a received signal in the form of a beam rotatable about a given axis, and having two signals of a given amplitude varying as sine and cosine functions respectively, in accordance with the rotary position of the beam, and a third signal having a value equal to half said given amplitude, comprising means for receiving energy from said beam, means for detecting said received energy, means for separating the three signals in said detected energy, means for determining the center of said beam, means for subtracting said third signal from the first and second signals to leave pure sine and cosine functions of said signal, and means for comparing the ratios of said subtracted signals to indicate the direction line in accordance with the beam center indication.

3. A beacon system for indicating direction of a receiver with respect to a beacon signal, comprising means for transmitting energy in the form of a beam rotatable about a given axis, means for modulating the energy of said beam with two signals varying as sine and cosine functions respectively, in accordance with the rotary position of the beam, and a third signal having a given value, means for receiving energy from said beam, means for detecting said received energy, means for separating the three signals in said detected energy, means for subtracting said third signal from the first and second signals, and means for comparing the ratios of said subtracted signals to indicate the direction line from said receiver to said transmitter.

4. A radio beacon system for indicating the direction line between a receiver and a transmitting beacon comprising a beacon transmitter for transmitting a signal in the form of a beam rotatable about a given axis, means for modulating the energy of said transmitter with two signals of substantially equal amplitudes varying as sine and cosine functions respectively, in accordance with the rotary position of the beam, and a third signal having a value substantially equal to half said equal amplitudes, means for receiving energy from said beam, means for detecting said received energy, means for separating the three signals in said detected energy, means for subtracting said third signal from the first and second signals, and means for comparing the ratios of said subtracted signals to indicate the direction line.

5. A radio beacon system for indicating the direction line between a beacon and a receiver, comprising a beacon transmitter for transmitting energy in the form of a substantially symmetrical beam rotatable about a given axis, means for modulating the energy of said transmitter with two signals of substantially equal amplitudes varying as sine and cosine functions respectively, in accordance with the rotary position of the beam, and a third signal having a value substantially equal to half said equal amplitudes, means for receiving energy from said beam, means for detecting said received energy, means for separating the three signals in said detected energy, means for determining substantially the center of said received beam, means for subtracting said third signal from the first and second signals, and means for comparing the ratios of said subtracted signals to indicate the direction line in accordance with the beam center.

6. A radio beacon system comprising first, second and third sources of energy at different given frequencies, said first and second sources producing output energy of the same given amplitude and said third source producing output energy at a different given amplitude, a rotatable unidirectional antenna system, means for producing sine and cosine function variations respectively, in said first and second output energies in accordance with the rotatable position of said antenna, a radio transmitter, means for modulating the energy in said radio transmitter with said varied first and second signals and with said third signal, and means for radiating said modulated energy from said rotatable antenna.

7. A radio beacon comprising first, second and third sources of energy at different given frequencies, said first and second sources producing output energy of the same given amplitude and said third source producing output energy at half said given amplitude, a rotatable unidirectional antenna system, means for producing $1+\sin$ and $1+\cos$ variations respectively, in said first and second output energies in accordance with the rotatable position of said antenna, a radio transmitter, means for modulating the energy in said radio transmitter with said varied first and second signals and with said third signal, and means for radiating said modulated energy from said rotatable antenna.

8. A radio beacon receiver for receiving energy from a rotatable beam modulated with first, second and third energies at different given frequencies, said first and second energies having the same given amplitude and $1+\sin$ and $1+\cos$ variations respectively, and said third source producing output energy having half said given am-

plitude, comprising a radio receiver for receiving energy from said beam and detecting said energy to reproduce energy at said first, second and third signal frequencies, means for separating said signal frequencies, integrating means for integrating said first, second and third separated signals, combining circuits for subtracting energy of said third signal after integration from the energy of said first and second signals respectively, to produce output signals corresponding to pure sine and cosine functions, and means for indicating the ratio of the signal output from said combining circuits to determine the directive position of said receiver with respect to said transmitter.

9. A radio beacon system comprising first, second and third sources of energy at different given frequencies, said first and second sources producing output energy of given amplitudes and said third source producing output energy at a different amplitude, means for producing a rotatable unidirectional radiation, means for producing sine and cosine function variations respectively, in said first and second output energies in accordance with the rotatable position of said unidirectional radiation, a radio transmitter, means for modulating the energy in said radio transmitter with said varied first and second signals and with said third signal, means for radiating said modulated energy from said rotatable antenna, a radio receiver for receiving energy from said transmitter and detecting said energy to reproduce energy at said first, second and third signal frequencies, means for separating said signal frequencies, combining circuits for subtracting energy at said third signal from the energy of said first and second signals respectively, to produce output signal envelopes corresponding to pure sine and cosine functions, and means for indicating the ratio of the signal output from said combining circuits to determine the directive position of said receiver with respect to said transmitter.

10. A radio beacon system comprising first, second and third sources of energy at different given frequencies, said first and second sources producing output energy of given amplitudes and said third source producing output energy at a different amplitude, means for producing a rotatable unidirectional antenna system, means for producing sine and cosine variations respectively, in said first and second output energies in accordance with the rotatable position of said antenna, a radio transmitter, means for modulating the energy in said radio transmitter with said varied first and second signals and with said third signal, means for radiating said modulated energy from said rotatable antenna, a radio receiver for receiving energy from said transmitter and detecting said energy to reproduce energy at said first, second and third signal frequencies, means for separating said third signal frequencies, integrating means for integrating said first, second and third separated signals, combining circuits for subtracting energy of said third signal after integration from the energy of said first and second signals respectively, to produce output signal envelopes corresponding to pure sine and cosine functions, and means for indicating the ratio of the signal output from said combining circuits to determine the directive position of said receiver with respect to said transmitter.

11. A radio beacon system comprising first, second and third sources of energy at different given frequencies, said first and second sources producing output energy of the same given amplitude and said third source producing output en-

ergy at half said given amplitude, means for producing a rotatable unidirectional antenna system, means for producing $1+\sin$ and $1+\cos$ variations respectively, in said first and second output energies in accordance with the rotatable position of said antenna, a radio transmitter, means for modulating the energy in said radio transmitter with said varied first and second signals and with said third signal, means for radiating said modulated energy from said rotatable antenna, a radio receiver for receiving energy from said transmitter and detecting said energy to reproduce energy at said first, second and third signal frequencies, means for separating said signal frequencies, integrating means for integrating said first, second and third separated signals, combining circuits for subtracting energy of said third signal after integration from the energy of said first and second signals respectively, to produce output signal envelopes corresponding to pure sine and cosine functions, and means for indicating the ratio of the signal output from said combining circuits to determine the directive position of said receiver with respect to said transmitters.

12. A radio beacon comprising a transmitter for transmitting a directive radio energy beam, means for rotating said beam, a first means for modulating the energy of said beam with a signal varying as a sine function in accordance with the rotary positions of said beam, a second means for modulating the energy with a second signal varying as a cosine function in accordance with the rotary positions of said beam, and a third signal means for modulating the energy of said beam with a third signal having a substantially constant amplitude.

13. A radio beacon comprising a transmitter for transmitting energy in the form of a rotatable radio beam, a first means for modulating the energy of said beam with a signal of a first frequency varying as a sine function in accordance with the rotary position of said beam, a second means for modulating the energy of said beam with a signal of a second frequency varying as a cosine function in accordance with the rotary positions of said beam, and a third signal means for modulating the energy of said beam with a signal of a third frequency having a substantially constant amplitude equal to half the swing of said sine function.

14. A radio beacon comprising a transmitter for transmitting energy in the form of a rotatable radio beam, a first means for modulating the energy of said beam with a signal of a given amplitude varying as a $(1+\sin)$ function in accordance with the rotary position of said beam, a second means for modulating the energy of said beam with a second signal of said given amplitude varying as a $(1+\cos)$ function in accordance with the rotary positions of said beam, and a third signal means for modulating the energy of said beam with a third signal having a substantially constant amplitude equal to half said given amplitude.
